UNITED STATES PATENT OFFICE

2,561,928

WINDOW VENTILATOR FOR WARMING
INCOMING AIR

Lillian Stewart Johnston, Chicago, Ill.

Application May 28, 1947, Serial No. 750,960

9 Claims. (Cl. 219—34)

1

This invention relates to new and useful improvements in ventilators, and one of its principal objects is to provide a heating ventilator of improved design which is relatively simple and inexpensive to manufacture, and yet provides an efficient device for tempering the air which passes therethrough.

Another object is to provide a ventilator of improved design to afford greater heating efficiency than is now available in devices of a similar nature now found on the market.

It is another object to provide a ventilator which is extremely mobile in nature and is adapted to be used in various sized window frames or even mounted in the window itself.

It is a further object to provide a ventilator which is partially demountable so as to permit cleaning of all of its exposed elements with facility.

It is a further object to provide a ventilator which has means for directing a stream of air, after tempering, in a desired direction in the room.

It is another object to provide a ventilator which may be manufactured of transparent material and thus permit passage of light through the ventilator and an unobstructed view.

It is still another object of the invention to provide a ventilator having non-metallic heating elements which do not detract from the appearance of the ventilator and are preferably transparent in nature, in keeping with the teachings of the invention.

These and other objects of the invention will be apparent from a study of the accompanying drawings and the description which hereinafter follows.

Figure 1 is a view of the ventilator in perspective, positioned in a window sash, as seen from the inside of a room;

Figure 2 is a view of the ventilator in perspective, positioned in a window sash, as seen from the outside of a room;

Figure 3 is an exploded view in perspective of parts of the ventilator shown in Figures 1 and 2;

Figure 4 is a transverse sectional view taken on line 4—4 in Figure 1;

Figure 5 is an enlarged perspective view of the control mechanism used in operating the inlet opening in Figure 4;

Figure 6 is a perspective view of the ventilator, broken away at one end to expose the heating elements;

Figure 7 is a perspective view of another embodiment of the ventilator;

2

Figure 8 is a perspective view of another embodiment of the ventilator;

Figure 9 is a perspective view of the ventilator, broken away to show the arrangement of a modified form of heating element;

Figure 10 is a side view of the ventilator showing a modified form of inlet pipe; and

Figure 11 is a front view of a ventilator installed in a different manner from that shown in Figures 1 and 2.

The ventilator which comprises the instant invention has relatively few parts. It is comprised of a central box-like portion or housing 2 having telescopically arranged sections 4 and 6 which are adapted to engage the sides of the window frame upon installation of the ventilator in operative position. This is best shown in Figures 1, 2 and 3. The housing 2 and the end sections 4 and 6 are preferably made from glass, plastic or other transparent material, although any suitable material may be used. A gasket 3, made from any material such as felt, fiber, rubber or the like, may be provided about the external periphery of the ventilator to insure a sealed relation between the window sill, sash and the bottom of the window frame when the ventilator is in installed position.

In the embodiment shown in Figure 3, a heating element 8 is mounted in the housing portion 2 of the ventilator so as to divide the housing 2 into two chambers 5 and 7, best seen in Figure 4. This heating element 8 is preferably made from a piece of glass or plastic coated with a conductive material, such as Nesa glass, or of conductive glass, as is now found on the market. This element is an efficient heating material, and furthermore, is transparent to permit the passage of the sun's rays into the room where transparent material is used for the housing 2 and also permits an unobstructed view therethrough in keeping with the teachings of the instant invention. Perforations or apertures 10 are provided to permit air to pass from the one chamber 5 of the box-like structure into the other chamber 7, as best seen in Figure 4 by the arrows provided to indicate the flow pattern. These apertures 10 are provided only in the upper portion of the heating element 8 so that air must pass upwardly for a distance in chamber 5 of the housing 2, thus being heated before passing through the apertures 10 and into chamber 7 of the housing 2.

Inlet means 16 and outlet means 18 are provided on the outer and inner sides, respectively, of the housing 2. The inlet tube 16 is bent throughout its length to provide an angularly exposed entry orifice 20. The orifice 20 can be of

any suitable shape. The inlet pipe 16 is rotatably mounted on the outer wall 26 of the housing 2 to permit the exposure of the inlet orifice 20 in any desired direction. Thus, if it is desired to increase the amount of air passing through the device, the inlet orifice 20 may be exposed windwardly. Further, during inclement weather, the orifice 20 can be exposed in a downward direction to prevent rain or snow from entering into the housing chamber 2. The inlet tube 16 could also be a U-shaped member 22, as shown in Figure 10. Such design affords a trap 24 so that in the event the orifice should be exposed to precipitation, the precipitation would not reach the interior of the housing 2. The U-shaped member 22 is rotatably mounted to the outer wall 26 in a similar manner to other embodiments heretofore described, and may be equipped with a control mechanism 36 subsequently described. Further, any of these embodiments, glass wool, or other similar material, may be put in the inlet tube 16 to filter the air before its passage through the ventilator.

An electrical socket 30 is provided and adapted to receive an electric plug 32. Suitable electric connections are made from the socket 30 (see Figures 1, 3 and 4) to the heating element 8 to provide electricity to heat the element 8. A suitable wire 34 is provided with means for attachment to an electrical outlet 35.

A control unit 36 is provided for turning the inlet tube 16 to any desired position. This unit is best seen in Figure 5. The control unit 36 is comprised of a handle 38 attached to a rod 40, which rod extends through the inner wall 28 of the housing 2, through the heating element or plate 8, and for a portion into the inlet tube 16. A slot 42 is provided adjacent the end of the rod 40 which is housed in a bushing 44. This bushing is supported by fingers 46 which are attached to the walls of the inlet pipe 16 and to the outer peripheral surface of the bushing 44. A pin 48 passes through the bushing 44 and is located in the slot 42 of the rod 40, permitting the rod 40 to be moved axially relative to the bushing 44. By turning the handle 38 in either direction, the inlet pipe 16 may be faced in the desired direction. On the rod 40 intermediate the handle 38 and slot 42 is positioned a plate 50 which is adapted to cover the opening 41 of the inlet pipe 16 when the rod 40 is pushed inwardly toward the housing 2, thus providing means to shut off the supply of air into the housing 2.

In Figure 6 is shown a housing 52, similar to the housing 2 shown in Figure 3. However, a different type of heating element is employed. The heating elements shown are a series of plates 14 composed of similar material to that used in heating element 8 shown in Figure 3 and described above. These plates 14 are arranged as baffles. The air entering through inlet pipe 54 and into housing 52 must negotiate the length of the housing 52, and the air stream therefore, will necessarily pass through and contact all of the baffles 14 interposed in its path, before being exhausted through the outlet pipe 56. Wires 58 are connected between the plates 14 to supply the plates 14 with current necessary for heating purposes.

Figure 7 shows a second embodiment of the ventilator. A housing 60 is provided, similar to the housing 2 shown in Figure 3 and the housing 52 shown in Figure 6. The housing 60 is composed of six walls 61, 62, 63, 64, 65 and 66. They are preferably made of glass, plastic or some

other transparent material. The inner surface of the walls 61, 62, 63, 64, 65 and 66 are coated with a conducting material, as the heating elements heretofore mentioned, to provide the heating surface to be used in tempering the air as it passes through the chamber. No other heating element is provided. Inlet means, not shown, and outlet means 68 are provided, as in the embodiment shown in Figure 1. The housing 60 is provided with extensible end portions 70 and 72 which are affixed to the end walls 61 and 65 of the housing 60. These extensible end portions are comprised of sheets 74 and 78, preferably made of transparent material, which are attached to the respective end walls 61 and 65 of the housing 60 by means such as welding. Additional transparent sheets 76 and 80 are provided and serve as the extending portions. Channel shaped means 82, 84, 86 and 88 are positioned over the corresponding ends of sheets 74 and 76, and sheets 78 and 80 to hold the sheets in operative position. These channel shaped means may be laid over the ends of the corresponding sheets and held in position by the bottom of the window sash on one side and the sill on the other, or may be affixed to the end walls 61 and 65 by any suitable means. Control means 36, as shown in Figure 5, may be provided for controlling the flow of air into the chamber from the outside, and for positioning the inlet means, as heretofore described. Other means, such as the closure member 108, may be substituted if such control means are not desired. Furthermore, since in this embodiment the walls of the housing 62 are heated, a protective grating of any type on the market may be provided if desired to protect persons from contact with the housing.

Figure 8 shows a third embodiment of the ventilator. Panel 90 in this particular embodiment is a window or any other suitable wall in which a ventilator may be mounted. The preferable form of this ventilator comprises a transparent tube 92 bent in a sinusoidal pattern. The tube is inserted in a hole 94 provided in the panel 90 and a gasket 96 of any suitable material is used to hold the tube in operative position. A heating element 98 in the form of a perforated disc, preferably made of glass, plastic or some other transparent material, and coated with a conductive material as disclosed above, is positioned in the tube 92 so as to extend substantially across the diameter of the tube 92. Wires 100 are secured to the heating element 98 and lead to a socket 102 located on the body portion of the tube 92. A suitable plug 104 and a wire 106 which are connected to a wall outlet are adapted to be inserted into the socket 102 to provide the necessary electric current. Closure member 108 is pivotally mounted adjacent the end of the tube 92 and adapted to be moved over the opening 110 leading into the room to control the current of air as desired. The tube 92 is rotatably mounted in the panel 90. It is contemplated that the inlet orifice 112 will be angularly exposed so that upon rotation of the pipe 92 the orifice may be exposed in any given direction. The inlet portion 114 of the pipe 92 may be designed as desired. It might be made similar to the inlet means 22 shown in Figure 10, so as to provide a trap 24, as described heretofore.

Figure 9 shows a housing 116 similar to housing 2 in Figures 1, 2 and 3 and 52 in Figure 6. A modified form of the heating element is disclosed. This heating element is comprised of a series of transparent cylinders 118 positioned

adjacent each other so as to effectively form a wall of cylinders. This wall divides the housing 116 into two chambers similar to chambers 5 and 7 shown in Figure 4. Apertures 120 are provided in these cylinders beginning at a distance above their bases to permit air to pass from one chamber of the housing 116 to the chamber on the other side of the cylinders. The cylinders 118 are made of a conductive material similar to the other heating elements heretofore described. The use of cylinders as heating elements greatly increases the available surface area for heating of the air passing therethrough. Inlet means and outlet means, not shown, may be provided in a manner similar to that heretofore disclosed in the embodiment shown in Figure 3. Control means 36, as shown in Figure 5, is also provided.

Figure 11 shows the ventilator mounted in a slightly different manner from that shown in Figures 1 and 2. In the mounting shown, the housing portion 122 of the ventilator is mounted in an opening provided in the corresponding panel 124 of the window or other panel into which the ventilator housing might be mounted. The ventilator housing may be supported adjacent the upper surface of the window frame 126. The opening between the window edges surrounding the ventilator housing 122 might be covered with putty or other sealing material 128. This sealing material would both seal any opening which might exist and serve to hold the ventilator housing in proper position.

The various embodiments of the ventilator heretofore disclosed indicate that the exhaust or outlet means leading into the room, such as 18 in Figure 1, 56 in Figure 6 and 68 in Figure 7, are preferably located toward the upper portion of the housings on which they are mounted. This is to take advantage of the air as it is heated and rises to the top of the housing, thus assuring the dissemination of tempered air immediately upon the heating of the element. As the air in the housing is heated and passes out through the exhaust pipe provided, fresh air will be drawn in through the inlet means such as 16 in Figure 2. This circulation through the housing may be increased by the exposure of the orifice in the inlet pipe in a direction from which the wind is blowing. The circulation may be shut off by use of the control means 36, as shown in Figure 5, to effectively block the entry of air through the housing.

From the foregoing description it is obvious that a ventilator, as constructed in accordance with the above disclosures and the teachings of my invention, is particularly well adapted for use where a heating ventilator is desired. Furthermore, where it is desired that the sun's rays shall not be blocked off nor the ventilator obstruct the view of those within the room, the transparent embodiments are particularly desirable. It is obvious that the description I have heretofore disclosed was made for purposes of describing my invention and that I do not in any way limit myself to the arrangement of parts or use of materials which might be in keeping with the teachings of my invention.

What I claim is:

1. A transparent ventilator device for windows comprising a housing made of transparent material, electrically conductive transparent surfaces inside of said housing adapted to be heated by an electric current, inlet and outlet means rotatably mounted on opposed sides of

said housing and operable from the sheltered side of the window to permit circulation of air through said housing, and a control means, said control means operatively connected to said inlet means and adapted to rotate said inlet means, said control means including a closure member adapted to regulate the passage of air through said inlet means into said housing.

2. A ventilator device for windows comprising a transparent housing, a transparent heating element mounted in said housing, inlet and outlet means provided on opposed sides of said housing, said inlet means provided with a bushing member mounted across its passage, transparent extensible end portions mounted on the opposed end walls of said housing, and a control means, said control means including a rod, a knob on one end of said rod, a longitudinal slot provided in said rod adjacent the other end of said rod, said rod in the vicinity of said slot being slidably mounted in the bushing member of said inlet means and operatively secured by means of a pin passed through said bushing member and said slot in said rod.
3. A transparent ventilator device for windows comprising a transparent housing provided with inlet and outlet means, said housing adapted to be mounted in a window, a perforated transparent electrically conductive heating element mounted in said housing and interposed between said inlet and said outlet means substantially normal to the direction of air flow, and means for regulating the circulation of air through said housing.
4. A transparent ventilator device for windows comprising a transparent housing having rotatably mounted inlet and outlet means on opposed sides of said housing, a transparent electrically conductive heating element comprising a plurality of perforated surfaces positioned adjacent each other and dividing said housing into a plurality of chambers, and control means, said control means regulating the flow of air through said housing.
5. A transparent ventilator device for windows comprising a transparent housing, said housing adapted to be mounted in a window, a transparent heating element mounted in said housing, said heating element having a transparent insulating base and a transparent electrically conductive coating, inlet and outlet means rotatably mounted on said housing, said inlet means having an angularly disposed orifice relative to the plane of the window, and a control means, operable from the sheltered side of the window, said control means adapted to rotate said inlet means so as to permit said orifice to be exposed in a plurality of directions.
6. A transparent ventilator device for windows comprising a transparent housing provided with inlet and outlet means on opposed walls of said housing, said housing adapted to be mounted in a window frame, transparent extensible end portions mounted on the opposed end walls of said housing, a transparent electrically conductive perforated heating element mounted in said housing and interposed between said inlet and said outlet means, and a control means, said control means adapted to regulate the circulation of air through said housing.
7. A transparent ventilator device for windows comprising a transparent housing, an apertured heating element of transparent electrically conductive material coated on a transparent non-conductive base mounted in said

housing so as to provide a plurality of chambers, inlet and outlet means provided on opposite sides of said housing to permit circulation of air through said housing, transparent end portions adapted to be telescopically mounted on said housing and control means adapted to regulate the circulation of air through said housing. 5

8. A transparent ventilator device for windows comprising a housing made of transparent material, transparent conductive surfaces inside 10 of said housing adapted to be heated by an electric current, inlet and outlet means rotatably mounted on opposed sides of said housing and operable from the sheltered side of the window to permit circulation of air through said housing, and a control means, said control means being adapted to engage said inlet means and to rotate said inlet means, said control means including a closure member adapted to regulate the 15 passage of air through said inlet means into said housing.

9. A transparent ventilator device for windows comprising a transparent housing having inlet and outlet means on opposed sides of said housing, an electrically conductive transparent 20 heating element comprising a plurality of transparent surfaces positioned substantially to divide

said housing into a plurality of chambers to provide a tortuous air flow path, and control means, said control means regulating the flow of air through said housing. 5
